(57) **CLAIM**

The ornamental design for a handle, as shown and described.

DESCRIPTION

FIG. 1 is a perspective view of a handle of the new design; FIG. 2 is a rear elevational view of the handle shown in FIG. 1;

FIG. 3 is a top plan view of the handle shown in FIG. 1; FIG. 4 is a left side elevational view of the handle shown in FIG. 1,

FIG. 5 is a front elevational view of the handle shown in FIG. 1;

FIG. 6 is a right side elevational view of the handle shown in FIG. 1; and,

FIG. 7 is a bottom plan view of the handle shown in FIG. 1. The portions of the Figures shown in phantom lines are not part of the claimed design and are for illustration only.
